LANTERN.

No. 21,732.

Patented July 26, 1892.

UNITED STATES PATENT OFFICE.

ARCHIBALD W. PAULL, OF WHEELING, WEST VIRGINIA.

DESIGN FOR A LANTERN.

SPECIFICATION forming part of Design No. 21,732, dated July 26, 1892.

Application filed May 16, 1892. Serial No. 433,222. Term of patent 14 years.

To all whom it may concern:

Be it known that I, ARCHIBALD W. PAULL, of Wheeling, in the county of Ohio and State of West Virginia, have invented a new and original Design for Lanterns, of which the following is a full, clear, and exact description, reference being had to the accompanying drawing, forming part of this specification, which shows a side elevation of a lantern showing my design, the unnecessary parts being omitted.

The leading feature of my design consists in a lantern having longitudinal flutings or

corrugations in the air-tubes, as shown in the drawing, the tube 2 having sets of flutings 3 15 between the bent portions 4, forming the corners.

I claim—

The design for a lantern, substantially as herein shown and described. 20

In testimony whereof I have hereunto set my hand this 13th day of May, A. D. 1892.

ARCHIBALD W. PAULL.
